ANDRE C. ATTENDU, OF MONTREAL, QUEBEC, CANADA, ASSIGNOR TO ATTENDU ENGINES LIMITED, OF MONTREAL, CANADA, A CORPORATION OF CANADA.

PROCESS OF REGULATING INTERNAL-COMBUSTION ENGINES.

Application filed December 27, 1921. Serial No. 524,987.

To all whom it may concern:

Be it known that I, ANDRE C. ATTENDU, a citizen of the Republic of France, and resident of the city of Montreal, in the Province of Quebec and Dominion of Canada, have invented certain new and useful Improvements in Processes of Regulating Internal-Combustion Engines, of which the following is a full, clear, and exact description.

This invention relates to Diesel and like engines and to an improved method of operating such. By Diesel and like engines is meant internal combustion engines in which during normal working the fuel is ignited by temperature and pressures developed upon compression.

The object of the invention is to improve the flexibility and efficiency of working of such engines by enabling approximately constant preignition pressure and temperature to be attained upon compression for all engine speeds. By aid of the invention the starting of an engine is facilitated.

The invention comprises an improved Diesel or like engine or a method of operating such wherein a working cylinder is provided with a charge of air available for compression which approximately fills the cylinder at all engine speeds and which is of a quantity that is varied in such a manner that as the speed of the engine increases the quantity decreases and vice versa whereby an approximately constant preignition pressure and temperature may be attained upon compression for all engine speeds.

The invention further comprises an improved Diesel or like engine or a method of operating such wherein a working cylinder is provided with a charge of air available for compression which approximately fills the cylinder at all engine speeds and the quantity of air available for compression in a working cylinder is controlled in such a manner that as the speed of the engine increases the quantity of the air is decreased and vice versa, by providing for the escape of controllable quantities of the air from a working cylinder whereby an approximately constant preignition pressure and temperature may be attained upon compression for all engine speeds.

The escape of air from the cylinder insures the efficient scavenging of the engine to eliminate burnt gas.

The Diesel principle, as is well known, is the compression of a charge of air to a point where the temperature and pressure conditions are such that fuel will ignite spontaneously. At the present time, this principle is put in practice in such a manner that a substantially fixed volume of air is taken into the engine cylinder at each stroke, regardless of the speed or temperature of the engine. When the engine is running at low speed and the compression of this charge is effected apparently slowly, the air friction is much less than when operated at high speed, with the result that the temperature does not rise as high with low speed compression as with high speed compression. Furthermore, with low speed compression more time is given for heat loss through the cylinder walls and in addition to this the less frequent explosions of low speed maintain a cooler cylinder wall. All these factors combine to keep the temperature from mounting when an engine is running at low speed and, as the pressure obtained is dependent to a certain extent on the temperature, it follows that the pressures when operating at low speed are much lower than the pressures obtained when operating at high speed. It follows, therefore, that when operating at low speed, a much smaller quantity of fuel can be burned than when operating at high speed, with the result that the power output of the engine drops more rapidly than the speed. In other words, the same results cannot be obtained with a Diesel engine as with a gasoline burning engine, which will consume at each explosion any amount of fuel within the engine capacity substantially without regard to the engine speed. This very material difference renders engines of the ordinary Diesel type unsuitable for uses such as the driving of automobiles, where a considerable power range is required at any engine speed according to the road conditions. It is well known that Diesel engines are difficult to start, the reason being found in the foregoing discussion. If an engine is designed when running cold or at low speed to give a pressure and temperature suitable for efficient combustion, it will be understood that the pressures and temperatures will be needlessly high when this engine runs at high speed. Diesel type engines are therefore designed for operation at their normal speed.

and when operated below this speed, the conditions are not suitable and when starting an engine, it is necessary to turn it over many times before the pressure and temperature will be built up to the point where combustion takes place spontaneously. This and the impossibility of hand-cranking a Diesel type engine are further reasons why it is unsatisfactory for uses such as automobile propulsion.

The present invention provides a method of control, which will ensure at low speed pressures and temperatures more nearly approaching those of high speed operation than has heretofore been possible. This means that an engine may be started with comparative ease and will deliver at low speeds considerable amounts of power, because with the relatively higher pressures and temperatures at low speed larger amounts of fuel may be burned at each explosion and greater power developed.

In the accompanying drawings which illustrate one form of apparatus constructed to carry out the invention;

Fig. 1 is a fragmentary side elevation of an engine of the Diesel type.

Fig. 2 is a vertical sectional view on the line 2—2, Figure 1.

Fig. 3 is an enlarged view partly in section of the air controlling means.

Fig. 4 is a section on the line 4—4, Figure 3.

Fig. 5 is a fragmentary view similar to Figure 1 illustrating a modification of cylinder construction.

Referring more particularly to the drawings, 11 designates the base or crank case of an engine upon which is mounted a plurality of power cylinders 12, 12^a—12^c. For each power cylinder there is provided a pumping cylinder, these cylinders being respectively designated 13, 13^a—13^c and being of greater volume than the power cylinders. The power cylinders and pumping cylinders may be in any suitable mechanical relation but it is at present considered preferable to arrange each pumping cylinder in axial alignment with the power cylinder with which it is associated, as clearly shown in the drawings. This arrangement enables considerable simplification in the manufacture and provides a compact arrangement and also other advantages which will be hereafter pointed out. With the axial alignment of the power and pumping cylinders, the pumping cylinder will preferably be of greater diameter than the power cylinder, as indicated, so that the ordinary type of trunk piston 14 of the power cylinders may operate through the pumping cylinders and leave an annular space of greater volume than the swept volume of the power cylinders. The pistons 15 of the pumping cylinders may be attached directly to or formed

integral with the power pistons and be operated by the same connecting rods 16, which under certain circumstances operate the power pistons. Each pumping cylinder is provided with an inlet port 17 controlled by a valve 18, which admits air from any suitable source, such as a manifold 18^a. The valves 18 may be of any suitable type, though at the present time revoluble valves of the type shown are considered preferable. Each power cylinder is provided adjacent its lower end with an exhaust port 19, which may be bridged as desired. An exhaust valve 20 is provided close to the port of each cylinder. These valves may be of any suitable type though at present the revoluble valve is considered preferable. The air inlet and exhaust valves 20 of the various cylinders may be arranged in alignment and have a common operating means, as shown, but if other types of valve are used the same result may be obtained by appropriate mechanism. Each power cylinder is provided with an air inlet port 21 controlled by a valve. In the form illustrated in Figures 1 and 2, the port is located at the top of the cylinder and the valve is designated 22, while in the form shown in Figure 5 the inlet port is disposed at the bottom of the cylinder with its upper end slightly below the upper end of the exhaust port 19, after the manner well known in the construction of ordinary two-cycle gasoline engines. In this latter disposition of the port, the piston 14 forms the valve controlling flow through the port. Each pumping cylinder 13 is connected by a passage or conduit 23 with one of the power cylinders. With the arrangement of cylinders illustrated, the connection is such that the pistons of connected pumping and power cylinders are working oppositely, so that when the piston of a pumping cylinder has completed its compression stroke, the piston of the power cylinder in connection with this pumping cylinder has completed its power stroke, as will be readily seen from Figure 1. It will be obvious that the connection of the pumping and power cylinders depends upon the formation of the crank shaft.

In order to effect the control of air emission, as previously stated, the exhaust valves 20 are provided with an adjustable driving connection in the embodiment illustrated. This comprises a driving gear 24 internally helically grooved as at 25. A helically toothed sleeve 26 is slidably but irrevolvably mounted on the operating shaft 27 of the valves 20 and may be held in any position in the length of the shaft by suitable means such as a controlling lever 28 engaging in a groove 29 of the sleeve. In order to secure proper relation in the operation of the valves 18 and 20, the same may be driven from a common source, for example, by the arrangement

ment illustrated. This arrangement comprises a driving gear 30 on one end of the series of valves 18 and a small pinion 31 at the opposite end of the series meshing 5 with and driving the pinion 24. With the design of engine illustrated, the air valve 18 is revolved at engine speed and the exhaust valve at half engine speed, but it will be understood that with different forms of 10 valves or engines operating on different stroke-cycle plans the speeds of valve operation will be altered.

The operation of the device is as follows:—

Assuming the parts to be in the position shown in Figure 1 and the crank shaft of the engine to be rotated, the pistons 14 and 15 are forced upwardly, the piston 15 compressing any air which is in the cylinder 13 through the conduit 23 leading to the power cylinder 12^a. At the same time, the piston 14 of cylinder 12^a, which is at the top of its stroke, descends and, at the proper moment when substantially the whole volume 25 of the power cylinder 12^a is clear, the air port 21 is uncovered by the valve 22 and the air compressed in pumping cylinder 13 rushes into the power cylinder 12^a. As the pumping cylinders have greater capacity 30 than the power cylinders, it will be understood that the air entering the power cylinder will at ordinary pressure occupy slightly greater volume than the power cylinder, so that there will be a slight initial 35 air pressure in the power cylinder. The piston of power cylinder 12^a now rises and further compresses this initial charge of air, with the result that the temperature rises to a point at which fuel will ignite. 40 On the up stroke of piston in cylinder 12^a, the compressor piston connected to it also rises and compresses air for delivery to the power cylinder 12. When the pressure and temperature in cylinder 12^a have reached 45 suitable degrees, that is, when the piston is at the top of its stroke, fuel is admitted in any suitable manner and immediately ignites, producing a very rapid combustion or explosion with consequent rapid rise 50 of temperature and pressure in the cylinder. This pressure exerts itself to drive the piston down until the port 19 is uncovered, whereupon the fluid escapes through the port. At the time the port uncovers, the 55 valve 20 is positioned to permit escape of the gas. This valve stays open until the piston reaches the extreme lower end of its stroke. The timing of opening of the port 21 is such that the air from the compressor 60 cylinder is admitted shortly after the exhaust port 19 is uncovered, with the result that the fresh air which has been compressed in the conduit 23 rushes into the power cylinder and drives out the burnt gas. 65 If the valve 20 closes at exactly the time the piston reaches the bottom of its stroke, such a quantity of air will be retained as is represented by the full volume of the cylinder or nearly the whole volume of air delivered by the compressor will be retained 70 in the engine cylinder. As the compressor cylinder has greater volume than the power cylinder, there may be therefore a slight super-atmospheric pressure in the power cylinder before compression by upward 75 movement of the piston commences. If, on the other hand, the valve 20 remains open at least until the power piston rises to cover the port 19, it will be apparent that some of the air admitted will be displaced by 80 the piston and forced out of the cylinder, so that compression will not commence at the beginning of the up stroke, with the result that a lower ultimate compression pressure is obtained in the cylinder. Assuming 85 for example that the volumes of the power and compression cylinders are in the ratio of 1:1.25 and that the depth of the port 19 is one-seventh the depth of the cylinder and one-sixth the stroke of the piston, the following extremes of pressure conditions will be observed:—With the valve 20 closing at the extreme end of the piston stroke, the initial pressure in the cylinder will be 1.25 90 atmospheres, which on completion of the 95 stroke would represent a pressure of 8.75 atmospheres, (without considering the increased pressure due to increased temperature). If on the other hand the valve 20 does not close before the piston covers the 100 port 19, there will be an initial pressure in six-sevenths of the cylinder of 1.25 atmospheres, (without considering loss of pressure due to equalization through the open valve). On completion of the stroke there 105 will therefore be a pressure of only 7½ atmospheres (without considering the increase of pressure due to increase of temperature.) As a matter of fact, if the valve 20 does not close before the port 19 is covered by the 110 piston, there will be a very substantial drop in the initial pressure due to equalization through the open port valve with the outside pressure. In reality, the pressure at the 115 completion of the stroke would be only a little in excess of six atmospheres. It will thus be seen that by regulating the time of closing of the valve 20 the difference in pressure of approximately 1.75 atmospheres will result. When the increase in pressure due to the increase in temperature arising from compression is taken into account, it 120 will be seen that there will be a very marked difference in compression. When an engine is being started cold or is running at low speed, there is a considerable loss of compression heat through the cylinder walls, with a resulting reduction of pressure. When an engine is running at high speed, the cylinder walls are much warmer, owing 125 130

to the more frequent compressions and explosions, and there is much less time during each compressing operation for loss of heat, so that, starting with air charges equal as to volume and pressure, the resulting pressure when operating at high speed is much greater than the resulting pressure when operating at low speed. This difference is compensated for in the present invention by regulating the volume or pressure of air at the commencement of compression to provide a greater volume or higher initial pressure for low speed than for high speed. The result is that, when running at low speed or when starting the engine, the preignition pressures and temperatures obtained upon compression approach more nearly to the preignition pressures and temperatures of high speed operation, in which a smaller quantity of air is found at the commencement of compression. This means that when running at low speeds or when starting a cold engine the conditions approach those obtaining when the engine is running at high speed. Under these conditions, the engine will start very easily and will operate at low speeds with very nearly the same efficiency as at high speeds.

The proportionately higher pressures thus obtainable at low speed enables a larger amount of fuel to be burned at low speed than is possible in Diesel type engines as ordinarily constructed, with the result that materially greater power may be developed at low speed than has heretofore been possible. This effect imparts to an engine according to this invention flexibility of control, as it enables the power delivered to be varied independently of the speed. The engine should be designed so that when operating with the minimum quantity of air such is adequate for the combustion of the maximum quantity of fuel that may be demanded by load conditions.

Assuming that the gear 24 is held stationary and the sleeve 26 slid lengthwise on the valve shaft 27, it will be observed that, owing to the helical groove connection between the gear 24 and the sleeve 26, the sleeve will be compelled to partially rotate, the direction of rotation depending upon whether the sleeve is moved into or out of the gear. As the sleeve is irrevocably connected to the valve shaft 27, it follows that the valve shaft will receive the same rotation. Under service conditions the gear 24 has positive driving connection with the engine crank shaft, as have also the engine pistons. It therefore follows that if the sleeve is moved either in or out, the relation of the valves 20 to the pistons will be altered. This holds true when the engine is running, as the gear 24 cannot alter its speed relation with the crank shaft. The result therefore is that the valves 20 will receive movement in ad-

dition to that imparted by the crank shaft, so that they will be set ahead of the crank shaft or will receive motion opposite to that of the crank shaft so that they will be set back relatively to the crank shaft. This setting ahead or back of the valves will result in their covering and uncovering the ports 19 in different piston positions, so that the ports 19 will be closed either when the piston is at the extreme lower end of the stroke or when it is half covering the ports or not until the ports are entirely covered by the piston. Any suitable and conveniently disposed means may be provided to operate this sleeve but from a practical point of view, it is necessary that as fuel conditions are varied to cause increase in engine speed, the means for determining the quantity of air available for compression should be correspondingly or automatically operated to cause the quantity of air available to be decreased as the speed increases and vice versa. The functions of the valves 18 are obviously to close the ports 17 and permit compression of air by the pistons 15. As the pistons 15 have positive and unvariable connection with the crank shaft, it is not necessary to have any adjustment for the valves 18 and these may therefore be directly and positively driven from the crank shaft without any adjustments. In fact, this is highly desirable, as it ensures at each stroke the delivery of an accurately measured volume of air to a power cylinder and leaves all the adjustment to be made in the amount of air retained in the power cylinder. Obviously, the valves 18 might be adjustable to regulate the amount of air drawn in by the pistons 15 for compression, but this would introduce complications and it is even possible that the two adjustments might clash in the hands of an unskilled operator. The size of each compression cylinder will be proportionate to the size of the power cylinder to provide a sufficient supercharge of air to take care of the maximum difference of conditions for which the engine is designed. Obviously, there is nothing to prevent the valves 18 being set to close the ports 17 before the end in place of at the end of the suction stroke, so that the compression cylinders may make permanent delivery of air below their maximum capacity.

As previously stated, the air inlet ports of the cylinders are not uncovered until the pistons have uncovered the exhaust ports 19. This is obviously necessary as, if the air ports opened before the exhaust ports, the burnt charges in the cylinders would flow through the air ports in place of through the exhaust ports. The time of uncovering of the air ports is therefore set relatively to the uncovering of the exhaust ports, in such a manner as to ensure that gas pressure

in the cylinder will be below the pressure of the incoming air. This is effected by proper setting of the mechanism operating the valves 22 when such are used or by the proper positioning of the ports 21 when they are located to be uncovered by the engine pistons as in Figure 5. In either case the incoming air serves to drive out the burnt gases and effect a thorough scavenging or

10 cleaning of the cylinders. It is to be expected that a small amount of air will be lost in this scavenging operation but this is taken into consideration in fixing the relative sizes of the power and compression cylinders. While the connection between the compression cylinders and the engine cylinders has been illustrated as an arrangement of piping, it will be understood that this is purely a matter of design.

15 Having thus described my invention, what I claim is:—

1. A method of regulating high compression engines to operate at varying speeds consisting in adjusting the volume of air compressed in such inverse ratio to the rate of compression as to maintain constant ignition temperatures irrespective of variations of engine speed.

2. A method of regulating high compression engines to operate at varying speeds consisting in adjusting the volume of air compressed in such inverse ratio to the rate of compression as to maintain constant ignition temperatures irrespective of variations of engine speed throughout a wide range of engine speeds.

3. A method of regulating high compression engines to operate at varying speeds consisting in delivering a definite charge 40 of air to the working cylinder and regulating the proportion of the charge retained for compression in such inverse ratio to the rate of compression as to maintain ignition temperatures constant irrespective of engine speed.

4. A method of regulating high compression engines to operate at varying speeds consisting in delivering a definite charge of air to the working cylinder and regulating the proportion of the charge retained for compression in such inverse ratio to the rate of compression as to maintain ignition temperatures constant irrespective of engine speed.

5. A method of regulating high compression engines to operate at varying speeds consisting of injecting in the initial cycle a

superatmospheric charge of air into the cylinder prior to compression for development of ignition temperature on compression at minimum engine speed and releasing in subsequent cycles a portion of the superatmospheric charge of air in the working cylinder in such inverse ratio to engine speed as to maintain constant ignition temperatures.

6. A method of regulating high compression engines to operate at widely varying speeds, consisting in charging the working cylinder for each cycle of operation with a volume of air which is greater at atmospheric pressure than the volume of the working cylinder, compressing approximately the entire air charge at minimum speed and reducing the quantity of the air charge retained for compression when the speed increases and in such inverse ratio to the speed increase as to maintain approximately constant pre-compression pressures and temperatures for all cycles of operation irrespective of speed variations.

7. A method of regulating a high compression engine to operate efficiently at widely varying speeds, consisting in charging the working cylinder, for each cycle of operation, with a volume of air greater at atmospheric pressure than the volume of the cylinder, compressing approximately the full air charge at minimum speeds of rotation and reducing the quantity of air compressed for increased speeds and to a degree so proportioned with respect to the speed increase as to maintain approximately constant pre-compression pressure and temperature conditions irrespective of engine speeds.

8. A method of operating high compression engines at widely varying speeds, consisting in charging a working cylinder, for each cycle of operation, with a volume of air greater at atmospheric pressure than the volume of the cylinder and regulating escape of the air from the cylinder prior to compression and in such direct ratio with respect to variations of engine speed that as the speed of the engine varies the quantity of air retained for compression is also varied in such inverse ratio to the speed variations so as to maintain approximately constant pre-compression thermal conditions irrespective of engine speed.

In witness whereof, I have hereunto set my hand.

ANDRE C. ATTENDU
